UNITED STATES PATENT OFFICE

146,490

DESIGN FOR A COMBINATION DESK UNIT

Joseph J. Swartzmiller, Carnegie, Pa.

Application June 29, 1945, Serial No. 120,397

Term of patent 14 years

(CL. D48—20)

To all whom it may concern:

Be it known that I, Joseph J. Swartzmiller, a citizen of the United States and a resident of Carnegie, in the county of Allegheny and State of Pennsylvania, have invented a new, original, and ornamental Design for a Combination Desk Unit, of which the following is a specification, reference being had to the accompanying drawings, forming part thereof, wherein

I claim:

The ornamental design for a combination desk unit, substantially as shown.

JOSEPH J. SWARTZMILLER.
